United States Patent

Des. 240,235
Patented June 8, 1976

240,235

TELEPHONE OUTLET RECEPTACLE

Edward Dennman Bunnell, Palm Harbor, Fla., assignor
to AMP Inc., Harrisburg, Pa.

Filed Jan. 31, 1975, Ser. No. 546,049

Term of patent 14 years

Int. Cl. D13—03

U.S. Cl. D26—1 B

FIG. 1 is a perspective view of a telephone outlet receptacle showing my new design.

FIG. 2 is a top plan view thereof.

FIG. 3 is a side elevational view thereof.

FIG. 4 is a front elevational view thereof.

I claim:

The ornamental design for a telephone outlet receptacle, as shown.
